UNITED STATES PATENT OFFICE

154,801

DESIGN FOR A PRESSURE GAUGE

John N. Polivka, Minneapolis, Minn., and Francesco Collura, New York, N. Y., assignors to General Mills, Inc., a corporation of Delaware

Application June 5, 1947, Serial No. 139,480

Term of patent 14 years

(Cl. D52—1)

To all whom it may concern:

Be it known that we, John N. Polivka, a citizen of the United States, residing at Minneapolis, in the county of Hennepin and State of Minnesota, and Francesco Collura, a citizen of the United States, residing at New York, in the county of New York and State of New York, have invented a new, original, and ornamental Design for Pressure Gauge, of which the following is a specification, reference being had to the accompanying drawing, forming part thereof.

In the drawing

Figure 1 is a top plan view of a pressure gauge, showing our new design;

Fig. 2 is a side elevation of the device of Fig. 1; and

Fig. 3 is a front elevation of the device of Fig. 1.

In Figs. 2 and 3, a supporting member for the device is shown in dotted outline for illustrative purposes only.

We claim:

The ornamental design for a pressure gauge, as shown and described.

JOHN N. POLIVKA,
FRANCESCO COLLURA.
